HAND REEL FOR STORING FISHING LINES OR THE LIKE

William A. Stewart, 1605 E. Center St., Pocatello, Idaho

Filed June 10, 1959, Ser. No. 56,307

Term of patent 14 years

(Cl. D31—4)

FIG. 1 is a view in perspective of a hand reel for storing fishing lines or the like, showing my new design;

FIG. 2 is a top plan view of the same;

FIG. 3 is an edge elevation; and,

FIG. 4 is an elevational view taken from the left end of FIG. 3.

I claim:

The ornamental design for a hand reel for storing fishing lines or the like, as shown.
